UNITED STATES PATENT OFFICE.

HENRY D. WHIPPLE, OF ROCHESTER, NEW YORK, ASSIGNOR OF ONE-HALF
TO CHARLES L. TUTTLE, OF ROCHESTER, NEW YORK.

CURTAIN-FIXTURE.

SPECIFICATION forming part of Letters Patent No. 739,129, dated September 15, 1903.

Application filed August 22, 1902. Serial No. 120,722. (No model.)

To all whom it may concern:

Be it known that I, HENRY D. WHIPPLE, of Rochester, in the county of Monroe and State of New York, have invented a new and useful Improvement in Curtain-Fixtures, which improvement is fully set forth in the following specification and shown in the accompanying drawings.

5 My invention relates to curtain-fixtures generally; and it has for its main object an improved method of hanging and controlling the curtain-roller.

Another object of the invention is to construct the frame holding the curtain-roller so as to be adjustable as to length or distance 15 between the heads.

A further object of the invention is to form the heads of the roller-carrying frame with enlarged bearing-surfaces to glide smoothly 20 along the window-casing with the least friction and minimum abrasion.

Other objects and advantages of the invention will be brought out and made to appear in the following specification, reference being 25 had to the accompanying drawings, forming a part thereof, the invention being more particularly pointed out in the claims.

Figure 1 is an inside front elevation of a window with my improved fixture attached 30 in place, parts being shown in various positions by full and by dotted lines. Fig. 2 is a front elevation of parts at one end of the roller-frame, more fully showing the construction. Fig. 3 is a vertical cross-section of the 35 roller-frame, taken on the broken dotted line 3 3 in Fig. 1, showing the inner face of the end plate or head. Fig. 4 is a similar cross-section of parts on the dotted line 4 4 in Fig. 2. Fig. 5 is a side elevation of the device seen 40 as indicated by arrow 5 in Fig. 1, further showing the construction of the parts and the manner of hanging the curtain-roller, parts being broken out and other parts shown in various positions by full and by dotted lines. Fig. 6 45 is an elevation, partly in longitudinal section, of parts at one end of the curtain-roller, showing interior parts.

In the drawings is the casing of the window, *a b* being, respectively, the upper and the 50 lower sash.

B is a blank upper roller resting in hang-

ers *c c*, secured to the casing *A* at the top, provided with an ordinary ratchet *d* and detent-pawl *e*. The pendent cord *f* for turning the roller *B* is secured to the latter to wind 55 thereon in the usual manner.

g g are suspending straps or bands for the curtain-roller *C*, held in a light horizontal frame *D* beneath the primary upper roller *B*. These straps or bands take onto offset parts 60 *h h* of the frame *D* and pass at the rear side around the roller *B* on seats *i i*, the cord *f* passing onto the front side of the roller *B*. From this description of the parts it will be understood that if the cord *f* be pulled down- 65 ward at any time it will turn the roller *B* forward, and so wind up the bands *g g* and raise the roller-frame *D* and the curtain-roller *C*, with its curtain *E*. It will also be observed that if the cord be slightly pulled in a manner 70 to raise the pawl *e* off of the ratchet *d*, as appears by dotted lines in Fig. 5, and then allowed to slip through the hand the weight of the frame and the lower roller *C* will turn the roller *B* backward, the frame, with its 75 roller, thus descending by gravity, as from the position shown by full lines in Fig. 1 to the position shown by dotted lines, shading another and lower part of the window. The ratchet *d* is placed on the roller *B* so the pawl 80 normally prevents the descent of the roller *C* and the curtain, these being permitted to descend only when the pawl is lifted off of the ratchet by means of the cord, as stated. By these means the curtain-roller *C* may be 85 brought opposite or in front of any part of the window from top to bottom.

The roller-frame *D* is formed of two substantially crescent-shaped metal end plates or heads *k l*, connected by horizontal rods *m* 90 *n* in a vertical plane, the plates or heads being vertical and occupying planes at right angles with the plane of the casing *A* of the window. The ends of the rods are threaded and pass through openings in the heads, each rod being 95 provided with screw-nuts *o o* outside and inside of each plate, as shown in Fig. 2, the nuts being set firmly against the plates to give the frame rigidity. Furthermore, by turning the nuts one way or the other the plates may 100 be laterally adjusted to vary the distance between them.

The roller C is of common construction in curtain-fixtures, being hollow, as shown in Fig. 6, with an axial rod *p*, provided with a spiral revolving spring *r*. The wooden cylindrical body *t* of the roller is provided with a ferruled head *s*, pierced by the rod *p*, and in which it has bearing, the rod being adapted to turn independent of the body *t*. The spring *r* is attached at one end to the rod and at 10 the other to the head *s* to control the relative motions of the parts *p* and *t*. The rod is formed with an expanded part *u*, and the head *s* is provided with the usual pivoted dogs *v v*, engaging said part *u* to act against 15 the spring and keep it normally from turning the rod. The latter is formed with a flat head *w*, adapted to occupy a rectangular opening in the plate *k*, Fig. 3, in the usual manner, the roller having an axial journal *x*, 20 Figs. 2 and 4, at its opposite end, occupying a corresponding opening in the head *l*. With the parts thus constructed the curtain E may be more or less unrolled from the roller C to cover more or less of the window and also 25 moved as a body in vertical directions to cover any particular part of the window, high or low. The heads *k l* of the frame are furthermore formed with expanded parts *y y*, Figs. 2, 3, and 4, to meet and glide with minimum 30 friction along the casing A as the roller-frame is moved vertically along the window-casing in the act of shifting the curtain up or down before the window.

What I claim as my invention, and desire 35 to secure by Letters Patent, is—

1. In a device of the character described, a light frame comprising heads formed with extended parts *y*, rods connecting the said heads, a roller carried in said frame, a curtain mounted on the roller, an upper roller held to turn in fixed bearings at the top of the window-casing, means for suspending the lower roller from the upper roller, means for normally preventing the descent of the lower roller, and means for actuating said means to 45 permit of the lowering of the lowermost roller, substantially as and for the purpose specified.

2. In a device of the character described, the combination with the casing, of hangers secured thereto at the top, a blank upper roller resting in said hangers and provided with a ratchet and pawl, a pendent cord for turning said roller and adapted to swing thereon, a curtain-roller suspended beneath said upper roller, suspending-straps for said 50 curtain-roller, a light horizontal frame carrying said curtain-roller, said straps engaging offsets in said frame and passing to the rear side of the upper roller, said frame being formed with expanded parts to glide along said casing as the roller-frame is moved vertically, substantially as described.

In witness whereof I have hereunto set my hand, this 20th day of August, 1902, in the presence of two subscribing witnesses.

HENRY D. WHIPPLE.
